(57) **CLAIM**

The ornamental design for a surgical guide member, as shown and described.

DESCRIPTION

FIG. 1 is a top view of a surgical guide member according to our new design;

FIG. 2 is a right-side view thereof, which is a right side relative to the front view in FIG. 3;

FIG. 3 is a front view thereof;

FIG. 4 is a rear view thereof, which is an opposite side from the front view in FIG. 3;

FIG. 5 is a left-side view thereof, which is opposite side from the right-side view of FIG. 2 and which a left side relative to the front view in FIG. 3;

FIG. 6 is a bottom view thereof, which is opposite the top view in FIG. 1;

FIG. 7 is a version of FIG. 2 with a callout 1 referred to for further illustrative detail in FIG. 9;

FIG. 8 is a version of FIG. 6 with a callout 2 referred to for further illustrative detail in FIG. 10;

FIG. 9 is an enlarged view thereof from callout 1 of FIG. 7; and,

FIG. 10 is an enlarged view thereof from callout 2 of FIG. 8.

The thick evenly dashed broken lines immediately adjacent to the shaded areas represent the bounds of the claimed design while all other thick and thin evenly dashed broken lines are directed to environment and are for illustrative purposes only. Both the thick and thin evenly dashed broken lines directed to environment in the drawings show portions of the surgical guide member that form no part of the claimed design.
